CONTAINER CLOSURE

John H. Murch, East Orange, N. J., assignor to
 American Can Company, New York, N. Y., a
 corporation of New Jersey

Application December 11, 1937, Serial No. 179,363

3 Claims. (Cl. 229—7)

This invention relates to containers for the packaging and delivery of liquids and more particularly to a sanitary fibre container for the packaging of liquid foods or beverages such as milk, fruit juices or the like wherein the element of sanitation is of considerable importance.

The present invention constitutes an improvement upon the container illustrated and described in John M. Hothersall Patent 2,085,979, granted July 6, 1937, and especially an improvement upon the top closure construction of said container. It advances the art a step further by providing an improved closure which will cover and protect that whole surface of the container with which the liquid product comes in contact as it is poured from the container, thereby further enhancing the sanitary qualities of this type of container.

An object of the present invention is the provision of a fibre package for milk and other beverages having a top closure construction which not only keeps the interior of the empty container in a sanitary condition from the container factory to the packer's plant, but also keeps the container in sanitary condition after it is filled with the beverage and especially that portion of the container which surrounds the pouring opening and over which the contents are poured and which is sometimes called the pouring lip.

Another object of the invention is the provision of a sanitary closure for a milk or the like container which not only completely and sanitarily seals the filling and pouring opening in a wall thereof and stays securely in place during shipment and handling of the container, but also extends its protective seal over the whole pouring area of the container wall and over the edges or joints of the container adjacent the pouring area.

Still another object of the invention is the provision of such a sanitary closure which may be readily opened, without any tool, by the fingers of the user and which will function as a reclosure and repeatedly protect the pouring area while the contents are intermittently poured out and consumed.

Numerous other objects and advantages of the invention will be apparent as it is better understood from the following description, which, taken in connection with the accompanying drawing, discloses a preferred embodiment thereof.

Referring to the drawing:

Figure 1 is a perspective view of a container

embodimenting the present invention and illustrating the same sealed and in the condition as it is received at the packing plant prior to filling with the desired product;

Fig. 2 is a top plan view of the same;

Fig. 3 is a detail vertical sectional view on line 3—3 of Fig. 2, showing the closure seated in place as it leaves the container factory; and

Fig. 4 is a similar fragmentary sectional view showing the closure sealed in place after the container is filled and as it leaves the packer's plant.

The container shown in the drawing is generally of the construction described in detail in said Hothersall Patent 2,085,979 and comprises briefly a substantially rectangular body 11, preferably formed from a single sheet of fibrous material folded to provide four side walls 12 and having the longitudinal edges of the sheet overlapped to form a vertical lap side seam 13.

The thus formed tubular body 11 has its marginal top and bottom portions beaded or necked in, that is to say each wall 12 is bent inwardly at 14, then outwardly at 15 and again inwardly at 16 to form an inner bead 17, a horizontal shoulder or end supporting ledge 18 and an end covering flap 19.

The top and bottom of the tubular body 11 is closed by means of substantially flat top and bottom disks 21, which are of a shape and dimension corresponding with the shape and dimension of a horizontal cross section of the container. In the preferred illustration of the drawing the ends are perfectly square.

Both ends being secured to the tubular body 11 in like manner the securing of the top closure need only be described.

The top disk or end closure 21 has its marginal outer part offset annularly from the plane of its main body to a width substantially equal to the width of the body ledge 18 upon which it rests and is supported, so that, when the covering flap 19 of the body is bent over and sealed to this offset part of the closure disk 21 the top surface of the flap 19 is preferably flush with the outer surface of the main body of the disk. A strong reinforced sanitary top joint is thus provided between the container body and end closure adapted to withstand the handling of the container incident to the shipment of the empty containers and the filling and shipment of the filled containers.

A suitable, sanitary, liquid proof and heat proof glue or cement, of which a variety are available is used in the formation of the side seam 13 and the top and bottom seams or joints.

The top end 21 is provided with a filling and pouring opening 22 which may be of any desired shape, a substantially triangular shape being shown in the drawing. This opening 22 is preferably located adjacent one corner of the top end and is closed and sealed by an auxiliary closure 23, which preferably is made from a single piece of fibre stock the same as the container or of other suitable material which can be cut and drawn to proper shape.

The closure 23 comprises a web or strip of material lying substantially flat over the exterior of the end 21 and extending from within one corner of the end to and over the opposite corner. It has preferably a rounded rear edge 24, a circular perforation 25, straight parallel side edges 26 and terminates beyond said edges 26 in a substantially triangular shaped web extension 27. The center portion of the closure 23 is secured to the end 21 in any suitable manner, as by staples or stitches 28. The portion of the closure 23 between its center and the web extension 27 is drawn into a cup shaped member or friction plug 29 of a shape and dimension corresponding to the shape and dimension of the opening 22 and this friction plug comprises an annular vertical friction wall 31 and a bottom 32, the wall 31 making frictional contact with the annular edge of the end 21 which defines the pouring opening 22, thus closing the latter.

The web extension 27 provides sufficient material to completely cover and protect the joint or seam formed between the body 11 and the end 21, between the points 33 which mark the termination of the edges 26 and the beginning of the web extension, and to also cover and protect the peripheral edge of the joint and to extend under the joint, terminating against the under-surface of the ledge 18.

Fig. 4 shows the closure 23 in its final sealing form or position. It will be noted that the vertical wall 31 (shown in Fig. 3) is here shown expanded or projected outwardly to form a locking bead or lug 34, which provides an additional locking means and assures a secure leak proof seal which even abnormally severe shipping and handling conditions are not likely to dislodge. This beading or lugging operation is of course performed in the packer's plant after the container is filled and initially sealed.

Before it leaves the container factory the finished container, including the closure 23, is completely coated inside and out with a suitable liquid proofing and stiffening material such as paraffin. Preferably the containers with the closures 23 in raised or open position are fed through a coating machine in which they are dipped or submerged in a bath of hot liquid paraffin and inverted and drained of any excess coating material, so that the whole inner and outer surface of the container and every corner and joint is completely and uniformly covered with the coating material. The closure 23 with its friction plug 29 is then pressed into sealing position. This coating and sealing operation is performed under practically sterile or micro-organism free condition and the hot paraffin itself has a sterilizing action upon all parts of the container.

After it arrives at the packer's plant and it is to be filled, the temporarily sealed container is opened by lifting the friction plug 29 from its sealing position and the milk or other product is filled through the filling and pouring opening 22 in a well known manner and the friction plug

is again pressed into sealing position and the extension 27 wiped or folded tightly over the container joint between the points 33, past the outer periphery of the seam and under the same.

When the closure 23 is opened and closed a hinging action takes place along a line of bend adjacent to the staples 28. The portion of the closure 23 rearward of the staples 28 may also be raised and lowered by a hinging action and used as a hanging support for the container, the aperture 25 being adapted to be slipped over a support such as a nail or hook.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A closure for liquid holding and dispensing containers, comprising in combination, a tubular fibre body having its top and bottom portions extending inwardly to provide end supporting outwardly projecting shoulders, end disks supported by said shoulders and sealed to said body by securing the marginal edges of said body over said disks in liquid proof joints, a said end disk having a pouring and filling opening adjacent a said joint, a closure including a friction plug to close and seal said opening, said closure having a portion thereof extended to completely cover said joint within the pouring area, said extension being folded over and under the adjacent of said shoulders to obviate the provision of auxiliary retaining means for said extension, whereby said extension covers the entire surface surrounding said opening with which said liquid comes in contact as it is poured from said container.

2. A closure for liquid holding and dispensing containers, comprising in combination, a tubular fibre body having its top and bottom portions extending inwardly to provide end supporting outwardly projecting shoulders, fibre end disks supported by said shoulders and sealed to said body by securing the marginal edges of said body over the marginal edges of said disks in liquid proof joints, a said end disk having a pouring and filling opening adjacent a said joint, a fibre closure including a friction plug to close and seal said opening, said closure being connected to said disk adjacent said opening, said closure having a portion thereof extended to completely cover said joint within the pouring area, said extension being folded over and under the adjacent of said shoulders to obviate the provision of auxiliary retaining means for said extension, whereby said extension covers the entire surface surrounding said opening with which said liquid comes in contact as it is poured from said container.

3. A closure for liquid holding and dispensing containers, comprising in combination, a rectangular fibre body having its top and bottom portions extending inwardly to provide end supporting outwardly projecting shoulders, fibre end disks supported by said shoulders and sealed to said body by securing the marginal edges of said body over the marginal edges of said disks in liquid proof joints, a said end disk having a pouring and filling opening adjacent a corner there-

of, a fibre closure including a friction plug for closing and sealing said opening connected to said disk and positioned substantially between two opposed corners thereof, said closure having a portion thereof extended to completely cover the pouring lip formed by said corner and adjacent joint, said extension being folded over and

under the adjacent of said shoulders to obviate the provision of auxiliary retaining means for said extension, whereby said extension covers the entire surface over which said liquid flows when it is poured from said container.
